UNITED STATES PATENT OFFICE

KONRAD BAYER, OF NUERMBERG, GERMANY

BRUSH BODY OF METAL

Application filed June 12, 1929, Serial No. 370,352, and in Germany June 20, 1928.

This invention relates to a brush with brush body of metal, and it has for its object to improve the fixation of the mountings of the bristle bundles in the holes of the brush head.

5 An embodiment of the invention is illustrated by way of example in the accompanying drawings in which:

Fig. 1 is a perspective view showing the 10 brush body from the lower side with several bundles of bristles inserted.

Fig. 2 is a cross section through the brush.

Fig. 3 is a longitudinal section through the brush body.

15 The brush body consists of a sheet metal plate *a* with downwardly turned longitudinal edges. In this sheet metal plate *a* ring-shaped sockets *f* are formed by pressing. The bristles *e* are mounted in metal sleeves

20 *c* having each at the upper edge a ring-shaped flange *d*. These sleeves *c* are inserted into the open upper end *b* of the sockets *f* so that the flanges *d* of the sleeves rest on the sheet metal plate *a*. The sockets *f* are arranged in 25 straight rows uniformly spaced from each other.

For the fixation of the bristle mountings *c* in the sheet metal plate *a* eyes *g* are arranged in said sheet metal plate between the rows 30 of holes *b* and on the two longitudinal edges of the sheet metal plate, said eyes being pressed out of the sheet metal plate. The eyes *g* are so high that they project over the ring-shaped flanges *d* of the sleeves *c*. Into 35 these rows of eyes *g* pins *i* are inserted which are so wide that they overlap the flanges *d* of two adjacent sleeves *c*. The pins *i* are long enough to extend through all the eyes *g* of one row. Each pin *i* has a hook *h* at one 40 end to facilitate the removing of the pin.

In the brush according to the invention the inserting and fixing of the bristle bundles is very simple, as it is merely necessary to pull out the corresponding pin *i* and, after having 45 interchanged the bristles, to reinsert the pin into the eyes *g*. The fixation of the bristle bundles is very reliable and secure, as each flange *d* of a metal mounting is held on two sides by the pins *i* and further strongly 50 pressed against the sheet metal plate *a*.

As shown on the drawing, the pins *i* are preferably of semicircular cross section although they might have any suitable shape.

The invention is not limited to flat brushes. The brush body may be for instance cylindrical, as is necessary for cylindrical brushes.

55 I claim:—

A brush having rows of sockets designed to receive sleeve-shaped metal mountings for bristle bundles having each a horizontal 60 flange at the upper end, eyes made in one piece with the sheet metal plate arranged in rows between the rows of sockets, and pins inserted one through the eyes of each row to overlap and press against the brush body the 65 horizontal flanges of two adjacent bristle bundle metal mountings.

In testimony whereof I affix my signature.

KONRAD BAYER.
